(57) **CLAIM**

The ornamental design for an oral irrigator handle, as shown and described.

DESCRIPTION

FIG. 1 is an isometric view of an oral irrigator handle showing our new design, our oral irrigator handle being attached to a nozzle, the broken lines illustrative of environmental matter only and form no part of the claimed design.

FIG. 2 is a top plan view thereof.

FIG. 3 is a front elevation view thereof.

FIG. 4 is a bottom plan view thereof.

FIG. 5 is a left side elevation view thereof; and,

FIG. 6 is a right side elevation view thereof,
